D 16.962

ESIGN.

—O—
N. PEAK.

WALL PAPER.

No. 16,962.

Patented Oct. 26, 1886.

UNITED STATES PATENT OFFICE.

WILLIAM N. PEAK, OF BROOKLYN, NEW YORK.

DESIGN FOR WALL-PAPER.

SPECIFICATION forming part of Design No. 16,962, dated October 26, 1886.

Application filed August 20, 1886. Serial No. 211,450. Term of patent 8½ years.

To all whom it may concern:

Be it known that I, WILLIAM N. PEAK, of the city of Brooklyn, in the county of Kings and State of New York, have invented and 5 produced a new and original Design for Wall-Paper, of which the following is a specification.

The nature of my design is fully represented in the accompanying print, to which reference is made.

10 The design consists, principally, of a foliated scroll, *a*, having curved branching leaves *b b*. The scroll partially surrounds a flower, *d*, composed of radiating leaves *c c* and a center piece, *e*. The scroll, flower, and leaves are 15 surrounded by stepped or correspondingly-notched borders *f g*, which form the outlines of the figures and leaves. A border, *B*, ap-

pears at one side of the foliated scroll and flower, separated from the ground *C*, on which they appear, by a line or stripe, *D*. Upon the 20 border appear numerous connected links *j* in the form of curves of beauty, forming a continuous chain, and these links *j* are outlined by the stepped corresponding borders, *k k*, as shown in the accompanying print. 25

I claim—

The design for wall-paper herein shown and described, the same consisting of a foliated scroll, *a*, curved branching leaves *b b*, flower *d*, leaves *c*, and center piece, *e*.

WILLIAM N. PEAK.
